UNITED STATES PATENT OFFICE.

DEWITT W. STRICKLAND, OF TYLERTOWN, MISSISSIPPI, ASSIGNOR OF ONE-EIGHTH TO
W. H. BRUMFIELD, ONE-FOURTH TO G. W. SUMMERALL, AND ONE-EIGHTH TO J. W.
SULLIVAN, ALL OF TYLERTOWN, MISSISSIPPI.

TRIGGER FOR DOUBLE-BARREL GUNS.

1,339,867.

Specification of Letters Patent. Patented May 11, 1920.

Application filed August 4, 1919. Serial No. 315,161.

To all whom it may concern:

Be it known that I, DEWITT W. STRICKLAND, a citizen of the United States, residing at Tylertown, in the county of Walthall 5 and State of Mississippi, have invented certain new and useful Improvements in Triggers for Double-Barrel Guns, of which the following is a specification.

This invention is a trigger for double 10 barrel guns and has for its object the provision of simple means whereby the trigger may be set to fire either barrel of the gun and after the gun is once fired will operate automatically to shift from side to side so as 15 to fire the barrels alternately.

The invention seeks to provide a device 20 for the stated purpose in which there will be means to prevent the trigger shifting after it has been set to one side and before 25 it has fired the gun and also in which there will be means for normally holding the trigger in a central or neutral position. Other 30 objects of the invention will appear in the course of the following description. The invention resides in certain novel features 35 which will be particularly pointed out in the appended claims.

In the drawings—

Figure 1 is a view partly in side elevation 30 and partly in longitudinal section of a portion of a gun having my improved trigger applied thereto;

Fig. 2 is a transverse section on the line 2—2 of Fig. 1 looking in the direction of 35 the arrow;

Fig. 3 is a transverse section on the line 3—3 of Fig. 1 looking in the direction indicated by the arrows;

Figs. 4 and 5 are transverse sections approximately in the plane in which Fig. 2 is taken but looking in the opposite direction and showing different positions of the trigger;

Fig. 6 is a detail perspective view of the trigger plate with the trigger mounted thereon and the parts coöperating with the trigger removed from the gun;

Fig. 7 is a detail perspective view of the sear-engaging portion of the trigger;

Fig. 8 is a detail perspective view of the fly or shipper.

The gun may be of any well-known type, Fig. 1 showing a portion of a well-known form of so-called hammerless gun and in 55 said figure the reference numeral 1 designates the trigger plate, 2 the guard around

the trigger, 3 the trigger, and 4 one of the barrels, 5 being the hammer controlled by the sear 6. A sear and hammer 5 are provided for each barrel and the sears are disposed immediately adjacent the side walls of the frame of the gun and are equipped at their rear ends with inwardly projecting lateral branches 7 which are adapted to be engaged by the trigger in the firing operation and thereby moved upwardly against the tension of the spring 8 which also acts upon the hammer 5 so that, when the sear is released, the hammer will be at once thrown against the firing pin and the gun fired. 65 The trigger 3 is pivotally mounted within the frame of the gun in the usual manner and in its upper portion adjacent its rear end is constructed with a transverse notch 9 in which is pivotally mounted a post 10 for 70 rocking movement transversely of the trigger. The upper end of this post is bifurcated, as indicated at 11, and in the bifurcation is mounted a roller 12 which is adapted to impinge against the branches 7 75 of the sears, as shown clearly in Figs. 2, 4 and 5, to release the sears, the roller reducing the frictional wear caused by the engagement of the parts in firing the gun. The lower end of the post 10 is flat, as shown 80 clearly in Figs. 2, 4 and 5, and in the trigger immediately below the post is a vertical chamber 13 to accommodate a spring 14 coiled around a plunger 15 slidably fitted in the trigger and provided with a head 16 held 85 against the bottom of the post 10 by the spring. The plunger 15 is mounted in the central longitudinal plane of the trigger and by its pressure upon the rocking post 10 tends to hold said post in the vertical plane 90 of the trigger and, therefore, in neutral position. As a result of this tendency of the post to remain in the neutral position it will be automatically returned to said position as it is retracted after firing either barrel and 95 will be, therefore, in position to engage the fly or shipper to be properly shifted when the gun is again fired. The pivot 17 of the post 10 projects beyond the rear end of the trigger in position to be engaged by the 100 trigger spring 18 so that the trigger will be normally held projected from the frame of the gun, or in its lowered position, and in the upper side of the trigger immediately in rear of the rocking post 10 is a V-shaped 105 notch 19 to accommodate a projection 20 on the rear side of the rocking post. This pro-

jection, as shown clearly in Figs. 3 and 7, is tapered toward both its upper and lower ends so that it will readily engage the parts with which it coöperates without unnecessarily limiting the lateral movement of the rocking post. It will also be readily understood upon reference to Fig. 3 that the lower end of this projection is adapted to engage the side walls of the notch 19 and thereby 5 limit the lateral movement of the rocking post so that it cannot be carried beyond the point where it will properly engage the sears. The fly or shipper consists of a ring or cylindrical body 21 pivotally mounted 10 upon the front side of a post 22 rising from the trigger plate 1 in rear of the trigger, the pivot for the fly consisting of a headed screw or pin 23, the head of which retains the fly upon the post 22. In its upper side, 15 the fly is provided with notches 24 disposed at opposite sides of its center and these notches are adapted to be engaged by a holding spring 25 secured upon the post 22 and projecting over the fly. It will be readily 20 understood that by engaging either of the notches 24 the spring holds the fly in the position in which it may be set. On the under side of the fly and diametrically opposite the ridge separating the notches 24 25 is a tooth 26 having beveled sides and at the junction of said sides with the peripheral surface of the fly are grooves or notches 27. The fly is so disposed that the tooth 26 will lie in the same vertical transverse plane as 30 the projection 20 upon the rocking post 10 so that as the trigger is raised in the act of firing the upper beveled end of the projection 20 will impinge against one side face of the tapered tooth 26, the engagement of the 35 upper end of the projection with the beveled or inclined side of the tooth 26 causing the post 10 to rock about its pivot so that the roller 12 will be caused to engage the branch 7 of the sear at that side of the gun toward 40 which the post has been rocked whereupon the barrel in advance of and in alinement with said sear will be fired. The continued 45 upward movement of the trigger in releasing the sear will bring the upper extremity 50 of the projection 20 in engagement with one of the notches 27 and this engagement will cause the fly to rock about its pivot as will be readily understood, the spring 25 shifting from one to the other notch 24 and 55 thereby holding the fly in the position to which it is shifted. The shifting of the fly will swing the tooth 26 across the central longitudinal plane of the trigger and the spring 25 will hold the fly in that position 60 while the trigger is withdrawing. As soon as the projection 20 clears the tooth 26, the plunger 15 will bring the rocking post 10 into its vertical neutral position whereupon the upper end of the projection 20 will be 65 disposed to engage what has become the

under side of the tooth. The said under side of the tooth will be engaged upon the next upward movement of the trigger and the trigger will be, therefore, shifted to the side opposite to that to which it was previously 70 shifted and, consequently, fire the unfired barrel.

In order that the trigger may be caused to fire either barrel at will, I provide means for shifting the fly manually previous to the firing of the gun and in addition to the means for automatically shifting the fly and trigger. To this end, a depending lug or arm 75 28 is provided on the under side of the fly in rear of the tooth 26 and in alinement therewith. In the sides of the frame 29 of the gun I secure sleeves or casings 30 in which are housed springs 31 and through which are slidably fitted plungers 32, the springs serving to hold the plungers normally in their outer positions. The plungers are located in alinement with and at opposite sides of the lug 28 so that if either plunger be pushed inwardly the inner end of the same will impinge against the lug 28 80 and will force the same to the opposite side of the trigger and thereby cause the trigger to act on that barrel of the gun which is at the same side as the plunger which was pushed inward. When the plungers are in 85 their outer positions their inner ends will be just beyond the limit of movement of the lug 28 so that they will not interfere in any way with the normal automatic operation. 90

The operation of the device is thought to 100 be evident from the description hereinbefore given and it will be noted that the device is exceedingly simple in construction and compactly arranged. It will be positive in its action so that the barrels of the gun will be 105 fired alternately and it will obviously operate as fast as the trigger can be actuated to fire the gun.

Having thus described the invention, what is claimed as new is:

1. In a double-barrel gun, the combination 110 of a trigger mounted for vertical movement, a rocking post carried by said trigger, means for shifting said post laterally as the trigger is raised, and a spring-controlled plunger mounted in the trigger and bearing upon the lower end of the post to hold it normally in central vertical position.

2. In a double-barrel gun, the combination 115 of a trigger mounted for vertical movement, a rocking post carried by said trigger and provided with an upwardly tapered projection on its rear side, a fly mounted above the trigger and in rear of said post and provided on its under side with a tapered tooth 120 arranged to be engaged by the projection on the post, the fly having grooves at the base of the tooth to be engaged by the end of the projection whereby the post and the fly will be successively shifted, and yieldable means 125 130

for engaging the fly and holding it in a set position.

3. In a double-barrel gun, the combination of a trigger having a notch in its rear end, 5 a rocking post carried by the trigger and having a projection playing in and engaging the walls of said notch to limit the lateral movement of the post, means for shifting the post laterally as the trigger is raised, and 10 means for returning the post to its neutral position as the trigger is lowered.

4. In a double-barrel gun, the combination

of a trigger, a rocking post carried by the trigger, a fly pivotally mounted in rear of the rocking post and above the trigger, said 15 fly being provided in its upper edge with spaced grooves, a spring latch mounted on a fixed support adjacent the fly and selectively engaging said grooves to hold the fly in a set position, and coöperating means on the rocking post and the fly to shift the post laterally to fire one barrel of the gun. 20

In testimony whereof I affix my signature.
DEWITT W. STRICKLAND. [L. s.]
